Fig. 3

Fig. 4

Fig. 5

Fig. 6

Fig. 7

Fig. 8

FIGURE 1 is a perspective view of flight embodying our new design and taken generally from the inner end and rear side thereof;

FIGURE 2 is a perspective view of the flight taken generally from the outer end and front side thereof;

FIGURE 3 is a rear elevational view of the flight;

FIGURE 4 is an inner end elevational view of the flight;

FIGURE 5 is an outer end elevational view of the flight;

FIGURE 6 is a front elevational view of the flight;

FIGURE 7 is a plan view of the flight; and

FIGURE 8 is a bottom view of the flight.

We claim:

The ornamental design for flight for an endless chain conveyor for a barn cleaner, substantially as shown.
